**TRIM RING FOR AUTOMOBILE WHEEL
OR SIMILAR ARTICLE**

Herbert Buerger, Walton, N.Y.

Filed Apr. 27, 1962, Ser. No. 69,872

Term of patent 14 years

(Cl. D14—30)

FIG. 1

FIG. 2

FIG. 1 is a side view of a trim ring for automobile wheel or similar article embodying my new design;

FIG. 2 is a cross sectional view taken on line 2—2 of FIG. 1.

I claim:

The ornamental design for trim ring for automobile wheel or similar article, substantially as shown.
